Primary Examiner — Mark T. Philipps

(57) **CLAIM**

The ornamental design for a media blasting device, as shown and described.

DESCRIPTION

FIG. 1 is a top, front, right side perspective view of the media blasting device according to our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a bottom, front, left side perspective view thereof;

FIG. 9 is a top, front, left side perspective view thereof; and, FIG. 10 is a bottom, front, right side perspective view thereof.

The dash-dash broken lines illustrate portions of the media blasting device that form no part of the claimed design. The dot-dash broken lines represent boundaries of the claimed design and form no part of the claimed design. The diagonal shading represents a transparent or translucent appearance.

1 Claim, 10 Drawing Sheets
